UNITED STATES PATENT OFFICE.

FRED T. LOBBEY, OF ST. LOUIS, MISSOURI, ASSIGNOR TO SULLIVAN MACHINERY COMPANY, A CORPORATION OF MASSACHUSETTS.

TRUCK.

Application filed March 29, 1921. Serial No. 456,605.

To all whom it may concern:

Be it known that I, FRED T. LOBBEY, a citizen of the United States, residing at St. Louis, in the county of St. Louis and State 5 of Missouri, have invented certain new and useful Improvements in Trucks, of which the following is a full, clear, and exact specification.

My invention relates to trucks and more 10 especially to mining machine trucks.

An object of my invention is to provide an improved means whereby a mining machine may be moved about a mine, the same being especially directed to the provision of 15 improved means whereby the machine may be transported up or down the sharp grades or pitches so often encountered in mine track. More specifically, my invention has for its object to provide an improved means 20 whereby the mining machine under its own power may be propelled about the mine under ordinary conditions and when a steep grade is encountered utilize its power in an improved manner to propel the machine up 25 the grade, the mechanism for accomplishing this propulsion being so designed as to supplement the tractive effort of the usual propulsion means and not to operate independently thereof. A further object of my invention is to provide mechanism which may 30 be operative in lowering the mining machine down grade in an improved manner under the control of an operator. Other objects of my invention will appear in the 35 course of the following specification and appended claims.

In the accompanying drawings I have shown for purposes of illustration one form 40 which my invention may assume in practice.

In these drawings,—

Fig. 1 is a side elevation of a mining machine and truck therefor equipped with one 45 form of my improvement, the machine being shown upon an up-grade.

Fig. 2 is a plan view of the construction shown in Fig. 1 with the mining machine removed from the truck.

Fig. 3 is an end view of the mining machine truck shown in Fig. 2, the view being 50 taken from the right hand end thereof with the reel removed to facilitate illustration.

Fig. 4 is a section on the line 4—4 of Fig. 53 in a plane extending longitudinally of the machine.

Fig. 5 is a similar view on the plane indicated by the line 5—5 of Fig. 3.

In the illustrative construction, it will be observed that I have shown a complete self-propelled mining machine 1 of standard 60 form mounted upon a usual transport truck 2 which is in turn carried upon wheels 3 adapted to move back and forth along the track 4. As in the usual construction, these wheels 3 are propelled through suitable 65 driving connections herein shown in the form of chain and sprocket connections 5 and 6, from a rear power shaft 7 preferably disposed transversely at the rear end of the truck and operatively connected through suitable 70 gearing, not shown, with an upstanding shaft 8 carried at the rear end of the truck, which in turn carries a gear 9 adapted to mesh with a corresponding gear upon the mining machine, so that the power of the 75 latter may be transmitted through the truck driving mechanism to propel the truck. As is usual the rotation of the shaft 7 is controlled through a well-known friction drive 13 controlled by a controlling wheel 14. A 80 cable reel 15 is carried by the rear end of the truck upon suitable support members 16 and this is driven by means of a friction wheel 17 engaging the rim 18 of one end of the reel 15 and in turn driven by a belt or chain 85 19 from the shaft 7.

Mounted on the shaft 7 is a spur gear 20 intermeshing with a spur gear 21 mounted upon a suitable stub shaft 22 and the spur gear 21 in turn meshes with a gear 23 secured to a transverse shaft 24 upon which is rotatably mounted a traction reel 25. Slidably mounted upon the shaft 24 is a clutch member 26 which, however, is keyed 90 to the shaft 24 and hence rotates therewith. The clutch member 26 is provided with 95 projections 27 adapted to interlock with projections 28 carried on the reel 25 and accordingly upon shifting of the clutch 26 toward the reel 25 the reel will be picked up by the shaft 24 and rotated therewith. A suitable oscillating clutch controlling 100 lever 29 is pivoted upon a short standard 30 upon the truck frame and is adapted to engage or disengage the clutch member 26 with the reel 25. For the purpose of controlling the rate of rotation of the drum or reel 25, I provide one head thereof with a collar 31 coaxially disposed with the drum and adapted to be engaged by a friction band 110

32 whose operation is controlled by a hand wheel 33 controlling a threaded rotatable shaft 34 which cooperates with a nut 35 secured to the free end of the friction band 32, 5 At this point, an important feature should be noted, which is that the peripheral speed of a cable wound upon the drum 25 is equal to the peripheral speed of the wheels 3 and accordingly that, though by reason 10 of the steepness of the pitch of a hill in the mine, the wheels 3 may slip and fail to grip the rails, when my improved auxiliary traction means is in operation the speed of motion of the truck will be the same as 15 would be the case were the wheels biting, and accordingly such traction as the wheels may obtain will assist the truck in advancing along the track. It will be understood that the reel 25 is disposed between the sides 20 of the truck and that a cable 36 is secured at one end thereto and is provided at its opposite end with a pin 37 by means of which it may be positively engaged with a point in advance of the truck in moving up 25 a hill.

From the foregoing description, the mode of operation of my improved construction will be readily apparent. When the machine in moving about the mine comes to a 30 hill too steep to be negotiated through the use of its ordinary truck driving mechanism, the flexible member 36, which may ordinarily be wound upon the drum, is unwound therefrom and connected to a fixed 35 abutment as, for instance, the member 37 disposed at a point further up the grade, or at the top of the same as conditions permit. After this connection has been made, the 40 clutch 26 may be thrown in, and by the positive traction afforded through the drum 25, the machine may be hauled up the grade. During the use of the drum 25, however, it 45 will be evident that the wheels 3 are still rotating and that their traction will accordingly aid very materially in moving the machine up the hill. During the process 50 of passing down a steep pitch, it will also be noted that by my improved means it is possible to regulate the speed of the truck as desired through simply the connecting of the flexible connection 36 at a point adjacent the top of a pitch and then allowing the machine to run down the hill 55 with the clutch 26 out and with the brake band 32 controlling the speed of the machine by its friction with the collar 31.

As a result of my improvement, it will be observed that the supplemental mechanism provided may be applied to a mining 60 machine truck of standard form without any change in the machine proper and with only a slight change in the truck and that it may remain upon the truck during use of the same under normal conditions without 65 in any way interfering with the movement

of the truck about the mine. It will also be observed that whenever it is desired to utilize my improved construction, the same may be very readily put into use by a very simple operation involving only the connection of the flexible member to a suitable fixed element. Attention is also directed to the fact that my improved mechanism may be very readily and cheaply manufactured and is of a rugged character well 70 adapted to service conditions. These and other advantages of my improvement will, however, be readily apparent to those skilled in the art. This application is a continuation in part of my application Serial No. 80 75 211,812, filed Jan. 14, 1918.

While I have in this application specifically described one form which my invention may assume in practice, it will be understood that this form of the same is shown 80 for purposes of illustration and that the invention may be modified and embodied in other forms without departing from its spirit or the scope of the appended claims.

What I claim as new and desire to secure 85 by Letters Patent is:—

1. In a mining apparatus, a mining machine, a truck frame relative to which said machine is bodily movable during loading and unloading, truck driving mechanism on said truck driven by said mining machine when in a predetermined position on said truck including a rotatable shaft and running gear driven from said shaft, a supplemental winding member driven from 90 said shaft and so disposed relative to the path of said machine as to permit free movement of the latter, and a flexible member wound on said member connectible to effect bodily movement of said truck. 95

2. In a mining apparatus, a mining machine, a truck frame relative to which said machine is bodily movable during loading and unloading, truck driving mechanism on said truck driven by said mining machine 100 when in a predetermined position on said truck including a rotatable shaft and running gear driven from said shaft, and supplemental means distinct from said running gear so disposed as to maintain the height of 105 the machine pathway close to the truck wheels during transport and operatively connected with said shaft whereby said truck may be propelled up an incline. 110

3. In a mining apparatus, a mining machine, a truck frame relative to which said machine is bodily movable during loading and unloading, truck driving mechanism on said truck driven by said mining machine when in a predetermined position on said truck including running gear, and supplemental means operatively connected therewith and rotating at a higher speed than 115 said running gear whereby said truck may be propelled up or lowered down an incline, 120

said means being so disposed relative to the path of said machine as to permit free movement of the latter.

4. In a mining apparatus, a mining machine, a truck frame relative to which said machine is bodily movable during loading and unloading, truck driving mechanism on said truck driven by said mining machine when in a predetermined position on said truck including a rotating shaft, a supplemental winding member driven by said shaft and so disposed as to maintain the height of the machine pathway close to the truck wheels during transport, and a flexible member wound on said member and connectible to a point exterior to said truck frame to effect bodily movement of the latter, the winding speed of said flexible member being substantially equal to the speed imparted to the truck by the truck driving mechanism.

5. In a mining apparatus, a mining machine, a truck frame relative to which said machine is bodily movable during loading and unloading, truck driving mechanism on said truck driven by said mining machine when in a predetermined position on said truck including a rotating shaft and supplemental truck propelling mechanism actuated by said shaft, to impart a movement to said truck substantially equal to the peripheral speed of the truck wheels, said supplemental mechanism being so disposed relative to the path of the machine as to permit free movement of the latter and to maintain the height of the machine pathway close to the truck wheels during transport.

6. In a mining apparatus, a mining machine, a truck frame relative to which said machine is bodily movable during loading and unloading, truck driving mechanism on said truck, driven by said mining machine when in a predetermined position on said truck normally operative to propel said truck, and supplemental truck driving mechanism adapted, when in operation, to cause the speed of the normally operative truck driving mechanism substantially to correspond to the speed of the truck, said supplemental mechanism being so disposed relative to the path of said machine as to permit free movement of the latter and to maintain the height of the machine pathway close to the truck wheels during transport.

7. In a mining apparatus, a mining machine, a truck frame relative to which said machine is bodily movable during loading and unloading, wheels and axles therefor, wheel driving mechanism on said truck driven by said mining machine when in a predetermined position on said truck including a rotating shaft other than the wheeled axles, supplemental winding means

driven by said shaft and adapted to cooperate in the propulsion of the truck, said supplemental mechanism being so disposed relative to the path of said machine as to permit free movement of the latter and to maintain the height of the machine pathway close to the truck wheels during transport, and means for controlling the connection between said shaft and driving mechanism.

8. In a mining apparatus, a mining machine, a truck frame relative to which said machine is bodily movable during loading and unloading, running gear for said truck frame, a shaft connected to said running gear driven by said mining machine when in a predetermined position on said truck to drive the same, supplemental truck propelling means consisting of a drum driven by said shaft and a flexible connection wound on said drum and adapted to be secured to a fixed point outside of said truck, said means being so disposed relative to the path of said machine as to permit free movement of the latter and to maintain the height of the machine pathway close to the truck wheels during transport.

9. The combination with a wheeled mining machine truck frame having guides adapted to slidably receive a mining machine and carrying truck wheel driving mechanism adapted in one position of the mining machine thereon to be operatively connected to the machine and driven thereby, of a supplemental propelling mechanism having a flexible member disposable longitudinally beneath said truck frame and a cooperating drum disposed on the rear end of said truck frame and driven by said truck driving mechanism.

10. The combination with a wheeled mining machine truck frame movable over a trackway having guides adapted to slidably receive a mining machine and carrying on its rear end a truck wheel driving element adapted to be driven by a mining machine, of supplemental propelling mechanism having a flexible guiding member disposable longitudinally beneath said frame substantially along the center line of the trackway and a cooperating drum therefor disposed on the rear end of said truck frame and driven by rotation of said element.

11. The combination with a wheeled mining machine truck frame adapted to carry a mining machine, of cable reeling mechanism including a reel carried on the rear end of said truck frame, and a supplemental winding drum carried on the rear end of said truck frame and carrying a flexible member, said drum having provision for power rotation by a mining machine on said truck frame and being so disposed relative to said reel as to permit the free rotation of the latter and permit said flexible mem-

ber being disposed longitudinally beneath said truck frame.

12. The combination with a wheeled mining machine truck frame adapted to carry a mining machine, of cable reeling mechanism including a reel carried on the rear end of said truck frame, and a supplemental winding drum carried on the rear end of said truck frame and carrying a flexible

member, said drum having provision for 10 power rotation by a mining machine on said truck frame to vary the length of said flexible member and said drum and reel being driven through a single power connection to said mining machine. 15

In testimony whereof I affix my signature.

FRED T. LOBBEY.
